UNITED STATES PATENT OFFICE.

JOSEPH C. BROWN, OF FITCHBURG, MASSACHUSETTS, ASSIGNOR TO BROWN BAG FILLING MACHINE COMPANY, OF FITCHBURG, MASSACHUSETTS, A CORPORATION OF MASSACHUSETTS.

HOPPER AND ARTICLE-ORDERING DEVICE.

Application filed May 31, 1924. Serial No. 717,129.

To all whom it may concern:

Be it known that JOSEPH C. BROWN, citizen of the United States, residing at Fitchburg, in the county of Worcester and

5 State of Massachusetts, has invented certain new and useful Improvements in Hoppers and Article-Ordering Devices, of which the following is a specification.

The invention has for an object to effect 10 improvements in hoppers or article feeding devices, particularly of the type illustrated in my co-pending application Serial No. 706,968 wherein it is desired to feed delicately coated articles to a guide slot. It is 15 an important aim of the invention to provide an improved hopper and ordering means whereby to minimize damage to articles such as pills, or other coated articles, or seeds, which are liable to damage by en- 20 gagement with rigid agitating devices or by abrasion due to friction between the articles themselves if an excessive quantity were superimposed during agitation. A further aim is to provide a hopper which may have 25 large capacity comparatively, and yet in a novel manner provide for the introduction of only a small quantity of stock over the entrance to the guide slot, or in that part of the device where the articles are required 30 to be agitated or moved to facilitate their entrance to the guide slot or channel. It is a further important object to so construct the appliance that by the use of a light bristle brush the articles may be moved 35 in a satisfactory manner, so that surface friction and abrasion thereon will be reduced to a minimum.

It is also an object to provide a novel structure in a container for the purposes involved. Additional features of invention as well as objects and advantages attained thereby reside in the structural details of the device, and the combination and arrangement of elements, as may be readily understood from the following description and accompanying drawings, wherein,

Figure 1 is a side elevational view partly in section of a pill sampling device in which my invention is embodied.

50 Figure 2 is a perspective of the drum and hopper with parts broken away.

Figure 3 is a fragmentary perspective of one channel entrance.

Figure 4 is a cross sectional view of the drum on the line 4—4 of Figure 1.

55 Figure 5 is a fragmentary elevation of a different driving means for the agitator shaft.

There is illustrated a pill sampling machine as disclosed in my co-pending application Serial No. 706,968 filed April 16th, 1924, for improvements in packaging machines, including a chute plate 10, provided with parallel grooves 11 to receive pills from a drum 12, mounted on the upper end of the chute. The form of the grooves and the manner of feeding of pills therethrough in the entry may be understood from the aforesaid copending application. The chute plate has a broadened part 13 at its upper end, upon which the drum 12 is mounted directly over the grooves 11, as indicated. The drum comprises two circular heads 14 cut away at one side so as to fit against the upper planiform surface of the plate 10, 70 to which they are secured by screws engaged through the under side of the plate, as shown. Extending from the chute plate at its junction with the heads at the upper or left hand side of the drum as in Figure 80 1, fitted to and secured upon the edges of the heads 14, there is a housing plate 15, while at the opposite side of the head another hopper and housing plate 16 is similarly secured at its upper part, its lower part being fitted between the side hopper plates 17, which are attached to the inner sides of the heads 14, and inclined downwardly and inwardly therefrom, their lower edge portions being spaced approximately 90 the same distance as the channels 11 of the chute plate. Extending from the lower junction of the chute plate with the heads 14, there is a lower hopper plate 18, fitted snugly upon the heads a short distance, and then bent to extend eccentrically under and in spaced relation with the lower edge of the hopper plate 16 and outwardly thereof in a divergent relation to form a hopper space between the two as shown. This plate 95 18 is attached to the side hopper plates 17 and also to upper side plate extensions 19,

100

which extend above the plates 16 and 17 a distance and are attached to the heads 14 at the outer side, as may be seen in Figure 5. The plates 18 and 19 have their edges disposed horizontally on a level with the top of the drum, or they may be extended thereabove, as found preferable, and in the latter instance, the plate 16 should also be extended to a similar height.

10 It is to be observed that by this construction an approximately cylindrical chamber is formed directly adjacent the channels 11 between the drum heads and plates 15 and 16—at one side of which chamber a hopper 15 is formed, which communicates with this chamber at its lower part, beneath the lower edge of the plate 16. This lower edge of the plate 16 is at a comparatively low level, and forms a narrow throat opening from the hopper portion 20. It is also to be noted that the upper parts of the plates 15 and 16 stop short of each other a considerable distance, the plate 15 extending only a short distance above the chute plate, while the plate 16 may be extended nearly or quite to the upper sides of the heads 14. This provides an access opening in the top of the chamber referred to, by which access may be readily gained directly to the channels of the chute plate, and as will hereinafter appear, any failure of the stock to feed by a jam at the entrance to this channel may be quickly remedied, on account of the very small quantity of stock which will be superposed over the channels themselves by reason of the construction employed, as the operator may quickly clear the entrance to the channel by loosening the jammed articles, or removal of any foreign object or particles which may have been introduced with the stock. In the chamber there is concentrically mounted a revoluble shaft 22, journalled suitably in the heads 14, which shaft may be operated by any suitable means, in the particular instance shown a crank arm 23 being secured on one extremity of the shaft without the drum, and an operating link 24 extended from the arm to be operated in a familiar manner from any crank or cam device conveniently available.

55 A brush 25 is shown mounted upon the shaft 22, the brush preferably has a series of good bristles of suitable length or equivalent elements, arranged to brush lightly against the stock entering the throat opening and moving toward the left from the right upwardly along the chute plate as exposed within the drum, causing articles engaged and moved therebefore to enter readily into the exposed portions of the channels 11. The brush may be constructed in various ways, but as illustrated in the particular embodiment shown, comprises a head 26 having the bristles set therein and

having two stems 27 engaged slidably through suitable apertures in the shaft 22. The stems may be secured adjustably by means of set screws 28 in suitable apertures in the shaft. It is to be noted that the brush is of a width to work readily between the lower portions of the side hopper plates 17, as may be readily understood from the showing in Figure 4. It should be noted that the lower portions of the side plates 17 approach most closely to each other adjacent the lower points at which the channels 11 are exposed in the drum, and the most closely spaced portions are located slightly within the channels 11, the plates 17 being fitted snugly against the lower plate 18 and the heads; and cut to fit against the chute plate. By reason of their inclination, they extend diagonally across the channels, so that entrances to these channels are formed with sides divergent upwardly, it being possible for pills to enter at the upper part of the opening only, from which point the articles may move downwardly in the channels of the chute plate by gravity. By reason of this construction, in the operation of the device, a series of articles cannot become jammed in the opening, and no wedging effect is readily possible. It is also to be noted that the brush stops short of the plates 15, 16, and 18 and tends to brush only lightly against the chute plate 10 where it is exposed in the drum.

Stock being introduced in the hopper proper 20', it will move by gravity into the chamber 20, but by the location of the plate 16 will not rise therein to a great height, and will be only brushed lightly by the brush when the latter is oscillated or rotated in the chamber. With the movement of the brush toward the left or rearwardly, stock will be propelled upwardly upon the chute plate and quantities of articles will thereby be moved along over the channel entrances 29 into which many of them will drop and move downwardly into the channels beneath the convergent parts of the plates 17. It is an advantage of the arrangement that the plates 17 over the channels sustain the weight of stock over the channel entrances and it will not impede the movement of articles after the stock passes into the channels. Wedging of the stock in movement from the drum into the chute plate will thereby be reduced to a minimum.

It may be found preferable to operate the brush so as to rotate continuously in one direction, and in this event, a simple pulley 23' may be provided upon the shaft 22, as shown in Figure 5, and operated by belt from a pulley. The entrances to the channels may of course be arranged otherwise than as described, and the entrance openings formed in various ways, as may be found preferable. It will be seen that a compar-

atively simple drum has been provided, having novel features and advantages of importance for the improvement of functions of this character, and it is easily constructed.

5 I claim:

1. A device of the character described, comprising a chute device having a stock guiding channel, a hopper device mounted thereon in communication with the channel 10 at one point, and including a plate portion crossing said channel diagonally, whereby to form V-shaped entrance to the channel, means for feeding and maintaining a small quantity of stock over the channel entrance, 15 and an agitator member movable therein longitudinally of the channel.

2. An article feeding means of the character described comprising an agitator chamber, a chute device having stock guiding channels therein opening into the agitator chamber, said chamber being open at its upper part at one side for observation and manual movement of stock, and a hopper having communication with the chamber 20 adjacent the opposite side and lower part only, whereby a small quantity of stock only may be fed into the chamber from the hopper and an agitator movable in said chamber.

25 3. A device of the character described comprising an approximately cylindrical agitator chamber having an access opening at its upper part extending more on one side than the other, a brush agitator movable therein concentrically and having parts 30 stopping short of the sides of the chamber, a

chute plate being extended at an incline across the lower portion of the chamber to be lightly brushed by said brush element.

4. An article of the character described, 40 comprising an inclined chute plate, having a guide channel therein open for its full width at a part thereon, a side hopper plate having a lower edge portion extended diagonally across the channel, means to feed stock in close proximity with the lower part of the opening of the channel adjacent the last named plate and means to move stock longitudinally along this diagonally extending portion of said plate for entrance to the wider part of the opening to the channel. 50

5. A device of the character described, comprising semi-circular heads having an inclined chute plate secured therebetween, a housing plate fixed with the heads at the upper part of the chute plate, a second similar plate at the opposite sides of the heads stopping short of the chute plate and a third plate similarly fitted at the lower part of the head abutting the chute plate but extending outwardly of the heads and eccentrically, whereby to form a cylindrical agitator chamber and a hopper and a restricted throat opening from the hopper to the chamber, the first and second named plates 60 stopping short of each other at the upper parts, and a revolvably mounted agitator device between the first and second named plates. 65

In testimony whereof, I affix my signature. 70

JOSEPH C. BROWN.
